ELECTRIC REGULATOR.

1,224,983.

Specification of Letters Patent.

Patented May 8, 1917.

Application filed April 9, 1915. Serial No. 20,133.

To all whom it may concern:

Be it known that I, THOMAS S. WATSON, a citizen of the United States, and resident of Milwaukee, in the county of Milwaukee and State of Wisconsin, have invented new and useful Improvements in Electric Regulators, of which the following is a description, reference being had to the accompanying drawings, which are a part of this specification.

10 The invention relates to electric regulators.

The object of the invention is to provide a regulator for maintaining approximately 15 constant the voltage on a regulated circuit operating at a voltage lower than that of the circuit from which it is supplied.

A specific application of the invention would be to maintain approximately constant 20 the voltage on the lamps in a station or building supplied from an electric railroad or other electric circuit on which the voltage may fluctuate through a considerable range. It is common practice to operate 25 the lamps of such an installation at a voltage approximately equal to the lowest voltage of the supply circuit in order that a fair degree of illumination may be obtained at all times, and to absorb the difference 30 between this voltage and that of the supply circuit in a resistance. A change in the number of lamps in the work circuit changes the current flowing, and therefore the absorption of excess voltage in the regulating resistance, which in turn causes variation 35 in voltage at the lamp terminals. A variation in voltage at the lamp terminals will similarly be caused by variation in the supply voltage.

40 It is the object of the invention to provide an automatic means for so varying the value of this regulating resistance as to maintain approximately constant the impressed voltage on the regulated circuit regardless 45 of the variation in the current required in the work circuit or the variation in voltage of the supply circuit.

The drawings show a diagrammatic illustration of the device embodying the invention 50 wherein the regulator is operating in connection with a lighting circuit, but its

use is not to be restricted to this kind of 55 circuit, as it may be employed in connection with other forms of work circuit.

The regulator consists of a plurality of electro-magnetic switches, A, B, C, D, E, F, G, H and I, each comprising a core S, 60 fixed contact J and movable contact 22 and each of said electro-magnetic switches being normally held closed by springs K, and adapted to be opened by energizing the 65 windings thereof. Each of these electro-magnetic switches, except the last one, I, has two independent windings, S' and S². The windings S' are connected in series, the complete circuit being in shunt to the 70 terminals of the work circuit through conductors 15 and 16 the latter of which is connected at 17 to the line, and therefore they and consequently the regulator are subject to the same variation in voltage as the work 75 circuit. The windings S² of each switch form a portion of a local circuit from the 80 fixed contact J of the succeeding switch through a conductor 20, winding S², conductor 21, the resistance of the succeeding switch and thence through a conductor 23 to the movable contact 22 of the succeeding switch. Each of the windings S² forms a holding 85 means for retaining its switch in open position.

A series of resistances, R' to R⁹ inclusive, 85 comprise the regulating resistance for the absorption of the excess voltage of the supply line above that required in the work circuit. The first electro-magnetic switch A has no auxiliary winding S² in the circuit 90 of its resistance R', but a conductor 18 leads from the line 12 to the fixed contact J of the switch A. The last switch I has no auxiliary winding S² on its magnetic circuit and a conductor 13' connects the contact 22 of said switch and the resistance R⁹ 95 to the conductors 15 and 13.

The movable switch contacts 22 of the switches A to I are connected to the succeeding fixed contact by the conductors 24, 25, 100 26, 27, 28, 29, 30 and 31 respectively.

The operation of the device is as follows:

Assuming no potential on the supply circuit, there would be no current flowing in 105

any of the windings of the electro-magnetic switches, but a circuit would exist from conductor 12 through conductor 18, contacts J and 22 of switch A through conductor 24 to contacts J and 22 of switch B through conductor 25, etc., through the other switches, to the contact 22 of switch I through conductor 13', to the work circuit consisting of conductor 13, lamps L and conductor 14, 10 to supply conductor 10.

The windings S' which will be called regulating windings are part of a shunt circuit starting from conductor 14 at one terminal of the work circuit, through conductor 17, windings S' to conductor 15, to conductor 13 which is the other terminal of the work circuit.

If a voltage is now applied to the supply conductors, a current will flow through the 20 switch members and the work circuit and a current will flow through the regulating circuit. If the voltage is raised above normal for the work circuit, the regulating windings S' will be energized sufficiently to 25 lift the plungers S of the electro-magnetic switches, and as all are set at approximately the same lifting point, all of the switches will tend to open. This will interrupt the direct circuit from the supply circuit to the 30 work circuit, and will insert the regulating resistance in series with the work circuit as follows:—

From line conductor 12 through resistance R' through conductors 23, 24, 20, windings S² and conductor 21 all of switch A through resistance R² and conductors 23, 25, 20, windings S² and conductor 21 all of switch B, and through resistances R³ to R⁹ inclusive and conductors as above to the work circuit 40 13, through the work circuit to the other supply line 10. The effect of this action is to insert all the regulating resistances in series with the work circuit, thereby protecting the work circuit from any excess voltage which might be injurious to it.

The winding S² of each electro-magnetic switch is cumulative in its action with winding S' therefore tending to destroy the sensitive action of the switch and to lock it in 50 the open position on current values which would normally be overcome by spring K which tends to close the switch, and short out of circuit the regulating resistance. The effect of the windings S² when in circuit are therefore to destroy the sensitiveness of response of the electro-magnetic switches to 55 changes in voltage across the work circuit.

If the insertion of the resistances R' to R⁹ lowers the voltage at the terminals of the 60 work circuit below normal, the switch I which is energized by only the regulating winding S' will close under the action of spring K, shorting out its corresponding resistance R⁹ and locking coil S² of switch H

thereby reducing the resistance in series 65 with the work circuit and tending to raise the voltage at the terminals thereof. The short circuiting of winding S² of switch H renders switch H again responsive to the winding S' only, and if the voltage of the 70 work circuit is still below normal, switch H will close, shorting out its resistance R⁸, and the winding S² of switch G. This action will be continued in direct sequence until the removal of resistance has increased 75 the voltage of the work circuit to a point above the minimum at which the switches close.

Further change in voltage across the work circuit may be caused by turning on additional lamps in the work circuit thereby increasing the current required in the work circuit which in turn will increase the voltage drop across the resistance remaining in circuit, thus lowering the voltage at the 85 work circuit. The effect of this change will be to continue in proper sequence the closure of the electro-magnetic switches, any one of which in turn unlocks the next switch and renders it sensitive so that it will in turn 90 respond to the voltage of the regulating circuit.

The reverse conditions, namely, turning off lamps in the work circuit will decrease the current required, thereby decreasing the 95 voltage absorbed in the series resistance and increasing the voltage at the terminals of the work circuit, will cause the various closed electro-magnetic switches to lift, inserting resistance. The tendency will always be for all the switches to lift simultaneously thereby protecting the work circuit against sudden excess voltage at its 100 terminals and to drop back in sequence cutting out the resistance until the proper balance is restored. Manifestly the same conditions may be obtained with a constant condition of the work circuit, and a varying voltage of the supply circuit, or by simultaneous change in conditions of the work 105 circuit and voltage of the supply circuit.

What I claim as my invention is:—

1. In an electrical system, the combination, with a supply circuit, of a work circuit of variable resistance, a plurality of resistances in series with the work circuit, a regulator circuit sensitive to changes in voltage in both the supply and work circuits, and means controlled by said regulator circuit to simultaneously cut into circuit and to successively cut out of circuit the said resistances to maintain approximately the voltage of the work circuit regardless of variation in voltage in the supply circuit and in the resistance of the work 120 circuit.

2. In an electrical system, the combination, with a supply circuit, of a work

circuit of variable resistance, a circuit including a plurality of resistances in series with said work circuit, a regulator circuit in shunt to the work circuit, and 5 means controlled by said regulator circuit to simultaneously cut into circuit and to successively cut out of circuit the said resistances to maintain approximately constant the voltage of the work circuit regard- 10 less of variation in voltage in the supply circuit and in the resistance of the work circuit.

3. In an electrical system, the combination, with a supply circuit, of a work circuit, 15 a circuit including a plurality of resistances in series with said work circuit, a regulator circuit in shunt to the work circuit and in series with said resistances, and means controlled by said regulator circuit so as to si- 20 multaneously cut into and to successively cut out of circuit the said resistances to maintain approximately constant the voltage of the work circuit.

4. In an electrical system, the combination, with a supply circuit, of a work circuit of variable resistance, a plurality of resistances in series with said work circuit, automatic means comprising a plurality of electro-magnetic switches set to operate at 25 the same voltage, each adapted to include or exclude from circuit a section of resistance, a regulator circuit including the windings of the electro-magnetic switches, said electro-magnetic switches being, through their 30 windings in the regulating circuit, responsive to the voltage of the work circuit so as to simultaneously cut into circuit and to successively cut out of circuit the said resistances to maintain approximately constant 35 the voltage of the work circuit.

5. In an electrical system, the combination, with a supply circuit, of a work circuit, a plurality of resistances in series with said work circuit, automatic means comprising 45 a plurality of electro-magnetic switches set to operate at the same voltage, each adapted to include or exclude from circuit a section of resistance, a regulator circuit including the windings of the electro-magnetic 50 switches in shunt to the work circuit and in series with said resistances, said electro-magnetic switches being through their windings in the regulating circuit responsive to the voltage of the work circuit so as to 55 cut in and out of circuit the said resistances to maintain approximately constant the voltage of the work circuit.

6. In an electrical system, the combination, with a supply circuit, of a work circuit, 60 a plurality of resistances in series with said work circuit, automatic means comprising a plurality of electro-magnetic switches set to operate at the same voltage, each adapted to include or exclude from circuit a section of

resistance, a regulator circuit including the 65 windings of the electro-magnetic switches in shunt to the work circuit and in series with said resistances, said electro-magnetic switches being through their windings in the regulating circuit responsive to the volt- 70 age of the work circuit so as to simultaneously cut into circuit and to successively cut out of circuit the said resistances to maintain approximately constant the volt- 75 age of the work circuit.

7. In an electrical system, the combination, with a supply circuit, of a work circuit, a plurality of resistance sections in series with said work circuit, a regulator circuit, 80 automatic means in said regulator circuit comprising a plurality of electro-magnetic switches, and holding coils for said switches, each of said switches adapted to include or exclude from circuit a section of resistance and a holding coil for a succeeding switch 85 to simultaneously cut into circuit or to successively cut out of circuit the said resistance sections to maintain approximately constant the voltage of the work circuit.

8. In an electrical system, the combination, with a supply circuit, of a work circuit, a plurality of resistance sections in series with said work circuit, automatic means comprising a plurality of electro-magnetic switches, and holding coils for said switches, 90 each of said switches adapted to include or exclude from circuit a section of resistance and a holding coil for a succeeding switch, a regulator circuit including the windings of the electro-magnetic switches in shunt to 100 the work circuit and in series with said resistance sections, said electro-magnetic switches being through their winding in the regulating circuit responsive to the voltage of the work circuit so as to simultaneously 105 cut into circuit or to successively cut out of circuit the said resistances to maintain approximately constant the voltage of the work circuit regardless of variations of current in the work circuit.

9. In an electrical system, the combination, with a supply circuit, of a work circuit, a plurality of resistance sections in series with said work circuit, a regulator circuit, 115 automatic means in said regulator circuit comprising a plurality of electro-magnetic switches, and holding coils for said switches, each of said switches adapted to include or exclude from circuit a section of resistance and a holding coil for a succeeding switch to cut into or out of circuit the 120 said resistance sections to maintain approximately constant the voltage of the work circuit and to render the succeeding switch more or less sensitive to current variations.

10. In an electrical system, the combination, with a supply circuit, of a work circuit, a plurality of electro-magnetic switches,

a regulator circuit for operating said switches, a holding coil for each switch, a plurality of resistance sections in series with said regulator circuit, a section of resistance being controlled by each switch, said holding coils being in series with said resistance sections and each coil being controlled by the succeeding switch, each of said switches

being adapted to include or exclude its respective resistance to maintain approximately constant the voltage of the work circuit. 10

In testimony whereof, I affix my signature.

THOMAS S. WATSON.
